UNITED STATES PATENT OFFICE.

REUBEN E. BARBER, OF PITTSBURGH, PENNSYLVANIA.

DESIGN FOR A TOWEL-RACK.

45,515.

Specification for Design.

Patented Mar. 31, 1914.

Application filed January 28, 1914. Serial No. 815,091. Term of patent 7 years.

To all whom it may concern:

Be it known that I, REUBEN E. BARBER, a citizen of the United States of America, residing at Pittsburgh, in the county of Allegheny and State of Pennsylvania, have invented a new, original, and ornamental Design for Towel-Racks, of which the following is a specification, reference being had to the accompanying drawing, forming part thereof.

The figure is a perspective view of a towel rack, showing my new design.

I claim:

The ornamental design for a towel rack, as shown.

In testimony whereof I have hereunto set my hand.

REUBEN E. BARBER.

Witnesses:

M. A. KELLER,
SUE B. FRITZ.
